US00D961429S

(12) **United States Design Patent** (10) **Patent No.:** **US D961,429 S**
(45) **Date of Patent:** **** Aug. 23, 2022**

(54) **WARMER FOR AN OPTICAL ANALYZER**

(71) Applicant: **FUJIFILM Corporation**, Tokyo (JP)

(72) Inventors: **Kunihiro Tanaka**, Kanagawa (JP);
Yutaka Senda, Kanagawa (JP)

(73) Assignee: **FUJIFILM Corporation**, Tokyo (JP)

(**) Term: **15 Years**

(21) Appl. No.: **29/767,691**

(22) Filed: **Jan. 25, 2021**

(30) **Foreign Application Priority Data**

Jul. 28, 2020 (JP) ..... 2020-015661 D

CLAIM

The ornamental design for a warmer for an optical analyzer, as shown and described.

DESCRIPTION

FIG. 1 is a perspective view of a warmer for an optical analyzer, showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown are included for the purpose of illustrating portions of the warmer for an optical analyzer that form no part of the claim.

1 Claim, 7 Drawing Sheets
